(57) **CLAIM**

We claim the ornamental design for an articulated adapter for dispensing liquid primers, coatings and sealants, as shown and described.

DESCRIPTION

FIG. 1 is a front perspective view of the new design for an articulated adapter for dispensing liquid primers, coatings and sealants;

FIG. 2 is a front elevational view;

FIG. 3 is a side elevational view, the opposite side being a mirror image thereof;

FIG. 4 is a rear elevational view;

FIG. 5 is a top plan view;

FIG. 6 is a bottom view;

FIG. 7 is a front perspective view of an alternate embodiment of a new design for an articulated adapter for dispensing liquid primers, coatings and sealants;

FIG. 8 is a front elevational view of the embodiment of FIG. 7, with the opposite side being a mirror image thereof;

FIG. 9 is a side elevational view, the opposite side being a mirror image thereof; and,

FIG. 10 is a top plan view of the embodiment of FIG. 7; and wherein the bottom view of the embodiment of FIG. 7 is the same as FIG. 6.
